UNITED STATES PATENT OFFICE.

CARLETON B. GIBSON, JR., OF SAVANNAH, GEORGIA.

SPOTLIGHT SUPPORT.

1,405,111.

Specification of Letters Patent. Patented Jan. 31, 1922.

Application filed March 5, 1921. Serial No. 449,723.

To all whom it may concern:

Be it known that I, CARLETON B. GIBSON, Jr., a citizen of the United States, and a resident of Savannah, in the county of Chat- 5 ham and State of Georgia, have invented certain new and useful Improvements in Spotlight Supports, of which the following is a specification.

My present invention relates to improvements in lamps or projectors of the type known as spotlights, such for example as are used on motor cars, positioned in convenient reach of the operator whereby a light may be directed to the side of the road or other 10 desired point, such lights, however, being adapted for use on motor boats and other situations.

The present invention aims to provide an extremely simple and economical form of 20 lamp which may be readily manipulated by one hand of the operator to loosen the holding means of the lamp and at the same time, effect the positioning of the lamp to change the direction of the illuminating beam or to 25 entirely remove lamp from support for use as a trouble lamp.

A further object is to provide a construction in which one and the same handle will serve as both the friction controlling and 30 releasing means of the clamp and the lamp positioning or directing means.

A further object is to provide a mounting which may be readily attached to a wind- 35 shield having any "rake" or backward slope but which when once properly attached will not permit the axis of the beam of the lamp carried on this mounting to be elevated above the horizontal or such predetermined 40 position as may be required by law or be necessary to avoid directing offensive or dangerous glare into the eyes of an approaching driver or pedestrian. In like manner, move- 45 ment of the lamp beam in a horizontal instead of a vertical plane may be limited by using the same construction except that member 3 would be made straight instead of bent 90° as shown in Fig. 2.

With this and other objects in view, the invention includes the novel features of construction and arrangement and combination of parts hereinafter described and particu- 50 larly defined by the appended claims.

An embodiment of my invention is illus- 55 trated in the accompanying drawings in

Figure 1 is a side elevation partly in sec-

tion, illustrating my supporting and positioning means in connection with a lamp or projector of the type described, the latter being conventionally shown.

Fig. 2 is a rear elevation of the same.

Fig. 3 is a detail plan view of the form of blank from which the clamping arms are preferably made, and

Figs. 4 and 4^a are detail views of the 65 clamping bracket.

Referring by reference characters to this drawing, numeral 1 designates the lamp body or casing which is preferably provided with a rearwardly extended portion 1^a of 70 substantially truncated cone shape. Numerals 2 and 2^a designate two clamping arms, one of which (2) is secured to the rear face of the truncated cone portion 1^a while the other 2^a is hingedly connected to the portion 2 at 2^b conveniently by a spring hinge which may be formed by a reduced or narrowed integral connecting portion of the two arms which in the event of using an integral spring hinge would, of course, be 80 made of spring material. If desired, the arms may be made of two parts hinged together.

The arms are projected beyond the truncated cone shaped portion 1^a and are provided with opposed concave portions as indicated at 2^b and 2^c, these concaved or recessed portions being of substantially hemispherical shape and being designed to receive between them the spherical or ball-shaped member 3^a of the supporting bracket 3. These opposed portions of the clamping arms are in turn provided with suitable slots 2^d slightly wider than the adjacent portion 3^b of the supporting bracket. The slots 95 are so positioned as to permit limited movement of the clamp arms on the ball to swing the lamp in a vertical plane, the inner ends of the slots serving to limit the amount of vertical adjustment which may be secured. The slots may be made wide enough to permit a certain amount of vertical adjustment of the lamp, but are preferably so constructed as to width and so positioned as to prevent the lamp being adjusted to throw its 100 beams into the eyes of an approaching driver, or in other words, to always maintain the beam deflected downwardly.

The supporting bracket is provided with a suitable means for attaching it to the wind- 110 shield or other support, and a form of attaching means which I have found advan-

stageous is illustrated in the drawings, in which the horizontal arm 3^c is provided with a single hook or head 3^d formed integral with arm 3^c and of proper form for clamping against windshield standards or other supports. A member 4 cooperates with this head, which member is provided with two opposite hooks or heads 4^b which, with head 3^d and proper means for drawing them together, such as the U-bolt 5 and the nuts 5^a form a complete clamp.

The member 3^c is further provided with an annular groove 3^e for preventing movement of the U-bolt 5 along the axis of arm 3^c and the member 4 is further provided with a longitudinal groove 4^a which permits rotation of this member about the axis of arm 3^c, while otherwise maintaining the center line thereof substantially parallel to said axis. This whole arrangement gives the flexibility and range of adjustment of clamp member 4^b relative to arm 3^a necessary for attaching to tapered or sloping supports.

I prefer to construct the clamping arms from a single piece of stamped sheet metal as indicated in Fig. 3 in the shape of four substantially circular disc members connected by narrow necks, the disc members at the extremities being pressed into substantially hemispherical shape and connected to the adjoining disc members by the necks b and c, said adjoining disc members 2 and 2' being connected by the narrow neck d which forms the spring hinge hereinbefore referred to. The spring hinge is not necessary and may be replaced by a pin hinge as rotation of operating handle in proper direction positively opens or closes clamping members. The disc member 2 is provided with a plurality of annularly arranged openings designed to receive the bolts 6 which serve to connect it to the truncated cone portion 1^a of the lamp, and it is also provided with a central opening to permit the passage of the spindle hereinafter referred to, it being understood that the wall of the truncated portion is provided with corresponding openings.

The member 2' is likewise provided with a central opening for the passage of said spindle and annularly arranged openings designed to receive rivets which connect it to operating handle by means of member 2^x. The spindle is indicated at 7 and it has its inner end immovably secured in a suitable manner to the inner portion or arm 2 of the clamp. The outer portion of said spindle is provided with suitable cam means such that by rotation of the handle 8 in the proper direction, the outer arm of the clamp may be pressed towards the other member to cause the ball 3^a to be gripped with the desired degree of friction or to have said friction lessened or the clamping jaws separated sufficiently to permit of complete removal from ball 3^a, by the release of the arm 2', according

to the direction of rotation of the operating and directing handle 8. Said spindle 7 and handle 8 may be axially bored to take the common form of lamp focusing screw now in general use.

The preferred form of cam mechanism is shown in the drawings in which the handle 8 is provided with a screw threaded passage, the threads of which are designed to engage with corresponding threads formed on the spindle 7, said handle member being fastened to member 2' so as to only permit of rotary motion about its axis relative to member 2'. The elongated handle 8 may be grasped by one hand of the operator and, assuming the lamp to be frictionally held to the supporting bracket, may by a slight rotation in the proper direction effect the lessening of the friction grip sufficiently to enable the direction of the lamp to be readily changed by the action of the said hand on the handle. After the lamp has been adjusted to the proper direction a reverse rotation of the handle causes the clamp arms to again grip the ball with sufficient friction to hold the lamp in its adjusted position.

Furthermore, assuming the lamp to be frictionally held to the supporting bracket, the clamping arms may, by a few rotations of the handle 8 in the proper direction, be sufficiently separated to permit of entirely removing the clamp from the supporting ball 3^a, thereby permitting the entire releasing and removal of the lamp from the bracket, which is of great advantage in cases where it is necessary to change or repair tires or correct engine trouble at night, or otherwise use the lamp as a "trouble light."

I provide a simple, economical and durable construction, readily applied to the lamp and to the attaching bracket which will firmly hold the lamp in proper position under the vibrations of the vehicle to which it is applied, but which may be readily manipulated by the driver or operator by one hand, enabling him to always keep the other hand upon the steering wheel.

Having thus described my invention, what I claim is:

1. The combination with a lamp or projector of the class described of a two armed clamp having one of its arms secured to the back of the lamp, the arms of said clamp having opposed concave portions, a supporting bracket for said lamp having a substantially spherical head lying between said concave portions, a directing handle at the back of the lamp, and means whereby rotary movement of said handle actuates said clamp.
2. The combination with a lamp or projector of the class described of a two armed clamp having one of its arms secured to the back of the lamp, the arms of said clamp having opposed concave portions, a support-

ing bracket for said lamp having a substantially spherical head lying between said concave portions, a directing handle at the back of the lamp, screw means connecting said 5 arms, and a handle cooperating with said screw means and serving both to operate the clamp and manipulate the lamp.

3. The combination with a lamp or projector of the class described, of a clamp comprising two arms hingedly connected at one end and having opposed substantially hemispherical recessed portions at their free ends, one of said arms having a portion intermediate its ends secured to the back of the lamp, 15 a spindle firmly held relative to the arm so secured to the lamp, a directing handle rotatably but non-slidably held relative to the other arm of said clamp, cam means between said spindle and the other arm, and a supporting bracket having a substantially spherical head frictionally held between the recessed portions of said arms.

4. The combination with a lamp or projector of the class described, of a clamp comprising two arms hingedly connected at one end and having substantially opposed hemispherical recessed portions at their free ends, one of said arms having a portion intermediate its ends secured to the back of the lamp, 25 a spindle immovably held relative to the arm so secured to the lamp, a directing handle rotatably but non-slidably attached to the other of said arms, said handle having a portion provided with a screw threaded 30 opening and the spindle having screw threads engaging said opening, and a supporting bracket having a substantially spherical head frictionally engaged by said recessed portions of the arms.

40 5. The combination with a lamp or pro-

jector of the class described, of a two-armed clamp having its arms hingedly connected, each of said clamps comprising two disc-like portions connected by a relatively narrow neck, the disc-like portions at the ends of 45 the arms being shaped to provide opposed concavities, the other disc portion of one arm being secured to said lamp and the corresponding disc of the other arm being rotatably fastened to a handle having a threaded 50 passage, a spindle firmly held in said back wall and juxtaposed disc portion, and having a threaded portion engaging said threaded passage in said manipulating handle.

55 6. In a lamp support a bracket arm having a support engaging portion arranged substantially concentric with the axis of the arm, and a cooperating clamp member adjustable about the said axis.

60 7. In a lamp support, a substantially cylindrical bracket arm having an annular groove near its end, a clamp member cooperating with said grooved portion, said clamp having a base portion provided with a longitudinal groove engaged by said bracket arm, and a U-bolt for holding said arm in 65 said longitudinal groove.

65 8. In a lamp support, a substantially cylindrical bracket arm having an annular 70 groove near its end, a clamp member cooperating with said grooved portion, said clamp having a base portion provided with a longitudinal groove engaged by said bracket arm, and a U-bolt for holding said arm in 75 said longitudinal groove, said arm having an annular groove engaged by said U-bolt.

In testimony whereof, I affix my signature.

CARLETON B. GIBSON, JR.
